UNITED STATES PATENT OFFICE.

HARRY SOREF, OF MILWAUKEE, WISCONSIN.

DESIGN FOR A DISPLAY-STAND.

56,241.

Specification for Design. Patented Aug. 31, 1920.

Application filed June 23, 1920. Serial No. 391,226. Term of patent 7 years.

To all whom it may concern:

Be it known that I, HARRY SOREF, a citizen of the United States, residing at Milwaukee, in the county of Milwaukee and State of Wisconsin, have invented a new, original, and ornamental Design for Display-Stands, of which the following is a specification, reference being had to the accompanying drawing, forming part thereof.

The figure is a view in elevation of a display stand, showing my new design.

I claim:

The ornamental design for a display stand, as shown.

Signed at Milwaukee this 12th day of June, 1920.

HARRY SOREF.
